UNITED STATES PATENT OFFICE.

FRANCIS T. JOHNSON, OF CHICAGO, ILLINOIS.

SAFETY DEVICE FOR WRINGERS.

1,058,700.

Specification of Letters Patent.

Patented Apr. 8, 1913.

Application filed December 28, 1911. Serial No. 668,362.

To all whom it may concern:

Be it known that I, FRANCIS T. JOHNSON, a citizen of the United States, residing at Chicago, in the county of Cook and State of

5 Illinois, have invented a certain new and useful Improvement in Safety Devices for Wringers, of which the following is a specification.

My invention relates to means for releasing the rolls of wringers in emergency cases, and has for its object to provide a simple, safe and convenient apparatus whereby such release may be effected instantly by either hand or foot as may be desired and without danger to the wringer or its material parts.

The invention is illustrated in its general form in the accompanying drawings, wherein—

20 Figure 1 is a front elevation with parts broken away; Fig. 2 is a cross section along the line 2—2 of Fig. 1; Fig. 3 a side elevation of Fig. 1 with parts broken away.

Like parts are indicated by the same letters in all the figures.

A, A are the vertical side bars of the wringer, B, B the rolls and C a cross bar which is placed loosely in the space between the two portions of the vertical side bars.

30 Between the cross bar and the upper roll is disposed the tension springs D D.

E E are U-shaped clips which attach by a cross bolt E¹ to a block E² secured by the screws E³ to the side bars. A transverse bolt F in the upper part of each clip is preferably provided with a roller F¹ which bears upon the upper surface of the outer end of the cross bar C.

G G are links pivoted together at G¹ and 40 each notched at G² so as to engage each the upper portion of one clip. The pin J, which pivotally connects the two links G G, is adapted to slide in a slot J¹ in a standard J² which rises from the cross bar C. On 45 one end of the pin is downwardly depending bar J³ with a handle J⁴ and on the other end of the pin is a cord J⁵ adapted to run over pulleys J⁶ J⁷ on the cross bar. Thence it descends and is attached to the lever K, which projects from the fulcrum K² and terminates in the foot piece K³.

It will be understood that these devices thus described are illustrated more or less diagrammatically. The object is to show 55 one way in which my invention can be car-

ried out and applied to a wringer. Great modifications of the device could be made without departing from the spirit of my invention.

The use and operation of the invention is 60 as follows: Assuming that the device has been applied, the wringer will have the appearance substantially as indicated in Fig. 1, and the two wringer rolls will be forced together by the spiral springs in the usual 65 manner. In the meantime there is available and within easy reach in front of the operator either the handle or the cord leading to the foot lever. If the operator should get his hand between the wringer rolls or some 70 emergency should arise which would call for immediate release of the pressure which forces the two rolls together, the operator can either by pressing upon the foot lever or the handle J⁴ draw down the two links 75 and thus spread their ends. This action will immediately force the two clips outwardly, the action being facilitated by the clip rollers which move along the surface of the ends of the cross-bar. The cross-bar 80 being otherwise disconnected, is immediately disengaged and, the pressure on the spiral springs is relaxed.

I claim:

1. A safety device for wringer rolls comprising a frame, a cross-bar, springs between the bar and the rolls, clips pivoted on the frame adapted to overhang the ends of the cross-bar and means for pushing the clips outwardly to disengage the same and 90 release the cross-bar.

2. A safety device for wringer rolls comprising a frame, a cross-bar, springs between the bar and the rolls, clips pivoted on the frame adapted to overhang the ends of the 95 cross-bar and means for pushing the clips outwardly to disengage the same and release the cross-bar, said clips pivoted to blocks projecting from the side surface of the frame.

3. A safety device for wringer rolls comprising a frame, a cross-bar, springs between the bar and the rolls, clips pivoted on the frame adapted to overhang the ends of the cross-bar and means for pushing the clips 105 outwardly to disengage the same and release the cross-bar, said disengaging means comprising laterally pushing parts.

4. A safety device for wringer rolls comprising a frame, a cross-bar, springs between 110

the bar and the rolls, clips pivoted on the frame adapted to overhang the ends of the cross-bar, and means for pushing the clips outwardly to disengage the same and release 5 the cross-bar, said disengaging means comprising toggle bars whose ends engage the clips and means for depressing the other ends of the toggle bars.

5. A safety device for wringer rolls comprising a frame, a cross-bar, springs between the bar and the rolls, two holding devices for holding the cross-car to the frame and links pivotally secured together above the cross-bar their ends abutting the two holding 10 devices and means for pulling the ends 15

of the links down to disengage the holding devices.

6. A safety device for wringer rolls comprising a frame, a cross-bar, springs between the rolls and the ends of the cross-bar, clips pivoted to the frame and overhanging the ends of the cross-bar, toggle bars pivoted together above the cross-bar and adapted to abut the clips and means for pulling the inner ends of the toggle bars down to spread 20 25 the bars and disengage the clips.

FRANCIS T. JOHNSON.
